RADIO CENTERCASTING SELECTION
APPARATUS

Alfred N. Goldsmith, New York, N. Y.

Application June 5, 1942, Serial No. 445,859

5 Claims. (Cl. 235—52)

1

This invention relates in general to a centercasting system for effecting automatically an audit of listener station-selection, or, in other words, the summation and registration or recording of signal indications corresponding to radio broadcasting stations tuned in by listeners at their receiving stations. By "centercasting" is meant the art of radio polling. It involves the transmission from a group of respondent transmitting stations in the homes of individual voters to a central receiving station, of their opinions or reactions to questions which have reached them, generally by radio broadcasting. Centercasting is not recording, at the listener's home, the particular station to which he is listening. It involves necessarily securing his specific answers in appropriate form to particular questions.

In my copending application for "Radio centercasting system," Serial No. 421,898, filed December 6, 1941, now Patent No. 2,427,670, granted September 23, 1947, of which the present application is a continuation in part, there is described and claimed a system of communication between a central station and a multiplicity of remote or respondent stations whereby, for the purpose of gathering information such as public opinions, the system is operable to transmit from the central station to the various remote respondent stations a query upon which an expression of public opinion is desired, and thereafter each respondent registers his individual opinion at his polling station by means of a choice of any one of a number of votes, such votes being automatically transmitted from each respondent station to the central station, at which latter point they are accumulated and classified.

According to my present invention I propose to adapt the system of the aforesaid application with slight modification to enable it to function as a system for securing an automatic audit of the station-selection by broadcast listeners when it is desired to make a survey of the program preferences of a cross-section of the radio public.

Some of the objects of the invention are to determine by centercasting means, automatically, the particular broadcasting station to which each centercasting respondent has tuned his ordinary radio receiver at that time; to accomplish the above result regardless of whether push-button or single rotary knob tuning of the respondent's broadcast receiver is used; to carry out such an automatic audit of the selection of stations by the listener (respondent) either with or without the knowledge of the respondent, thus avoiding any psychological influence whatever of the respondent during the auditing period; to arrange that

5 the use of the broadcast receiver by the respondent shall place his centercasting equipment into condition for disclosure of his station selection, by automatic means which may or may not be known to the respondent; and to control the auditing (initiation and termination) or other functions from the central station of the centercasting system.

In carrying out my invention there is provided 10 an adjunct device which is associated with the tuning selector of a conventional radio receiver whereby the selection of one of a predetermined group of stations causes a corresponding indication at a central receiving point whereat a multiplicity of such individual indications are substantially simultaneously collected and recorded or registered in a systematic manner.

It is first assumed that the respondent has in 15 his home the following; a complete centercasting respondent installation as shown in Figure 2 of the aforesaid copending application, and also a conventional broadcast receiver separate therefrom. The method of carrying out the invention involves substituting for the voting keys in Figure 2 of said application another set of keys or knob-controlled switches placed over or cooperating with the tuning push buttons or tuning knob of the broadcast receiver. In order to do this a 20 switch mechanism is provided at the centercasting transceiver whereby the push-button voting keys and their contacts are thrown out of circuit, being replaced by a new set of push buttons or contacts associated with the tuning means at the broadcast receiving set.

The novel features characteristic of my invention 25 are set forth with particularity in the appended claims. The invention itself, however, both as to its organization and mode of operation together with further objects and advantages thereof, will best be understood by reference to the following description taken in connection 30 with the accompanying drawing in which Figs. 1a and 1b show diagrammatically the system as a whole, Fig. 1a representing a respondent's centercasting transceiver and the apparatus associated therewith and Fig. 1b represents the central station; Fig. 2 is a view partly in section showing the push-buttons of a conventional broadcast receiver and the adjunct applied thereto; Fig. 3 is a view taken on line 3—3 of Fig. 2; Fig. 4 is a view 35 partly in section of a modification showing the invention applied to a receiver of the type provided with a single rotary control knob; and Fig. 5 is a view taken on the line 5—5 of Fig. 4.

Referring now to Fig. 1a the block R represents 40 the respondent's centercasting transceiver as

shown in my aforesaid application, except for the voting keys and switch contacts which are included within the block K, marked "Centercasting keys." The six leads, 1, 2, 3, 4, 5 and 6 from the tone generators 228—233 are connected to the switch blades of a six-pole double throw switch 7, one set of contacts, to the left of the switch blades, being connected to the contacts with which the centercasting keys cooperate, and the other set of contacts, to the right of the switch blades, being connected by way of the six-conductor cable C to respondent's conventional broadcast receiver B. The manner of connecting the several conductors of the cable to the actuating keys of the receiver will be described hereinafter. The several blades or poles of the switch 7 are interconnected to move in unison, a spring S being provided to normally urge the switch to the left or "centercasting" position. There is also provided an electromagnetic relay L which upon being energized is adapted to actuate the switch to the right or "Station audit" position. At the receiver the customary "on-off" switch cooperates with a pair of contacts one of which is connected directly to one terminal of the preferably silently operating relay L, the other contact being connected to the other terminal of the relay through the power supply source for the receiver. With the switch of the receiver B in the "off" position, the switch 7 will assume its normal position and the apparatus will be set to provide operation for centercasting. Upon turning on the receiver by the actuation of the switch to its "on" position the energizing circuit will be completed to cause the relay L to be energized with the result that the switch 7 is actuated to the right to condition the apparatus for "station audit" operation. At the same time a second relay M which is connected in parallel to the relay L will become energized to connect the transceiver to its power supply. The relay M may comprise the relay identified as 223 in Fig. 2 of my aforesaid application.

The energization of relay L is also under the control of a centercasting control unit T. This unit is connected for deenergizing relay L to establish centercasting conditions in response to suitable actuation such as the reception of a designated signal transmitted by the central station when a centercasting vote is to be registered.

The operation of the system for effecting a station audit is the same as that for centercasting which is fully described in my copending application, except that the operation of the present system is initiated by the selective actuation of the station selector of the conventional broadcasting receiver instead of the centercasting keys. In other words preparation for audit operation is made by depression of a push-button station selector including selector keys 19 to 23 (Figure 2), or tuning knob 51 (Fig. 4) either of which conditions one of the tone generators 228 to 233 for modulating the respondent station transmitter.

The central station of the system shown in Fig. 1 of my earlier application is represented diagrammatically in Fig. 1b of the present application, it being noted that the "vote counters" are identified in this application by the call-letters, "WEAF," "WOR," etc., of the broadcasting stations, whereas for centercasting the vote counters are utilized to indicate the nature or character of the vote.

The manner of connecting the receiver into the system will now be described with reference to Figs. 2 and 3. The front panel of a push-button

tuning broadcast receiver is designated by 11. The buttons 12 to 16 control or select the five generally preferred stations in the locality. These buttons are moved in the direction shown by arrow 17 to pick any particular station and are usually interlocked so that only one may be pressed down and remain down at a time. To adapt this broadcast receiver to automatic auditing by centercasting means, as regards the selected station at any time, the casing 18 is placed over the push-button section. This casing may either be attached to the receiver front by some such means as screw 39 or may be held in place by the multiplicity of strong U-spring grips 25, 26, and so on, which snap over the free edges of the tuning push-buttons. The spring grips such as 25 are connected to shafts such as 27 which pass through the casing 18 and are terminated in the substitute push-buttons 19 to 23 which are likewise reciprocable and which replace in their functioning the original push-buttons 12 to 16 of the broadcast receiver. It will be understood throughout that the mechanical details of this arrangement are not essential to the invention. The essential feature is that the original push-buttons of the broadcast receiver are substituted for by a new set of push-buttons mechanically associated therewith or connected thereto in such fashion that only the substitute set of push-buttons 19 to 23 operate the tuning mechanism of the broadcast receiver. The substitute buttons in turn also actuate what would otherwise be the "voting contacts" of the centercasting respondent station, which voting contacts have been transferred from the centercasting respondent station to a location within the casing 18 and associated, for each contact, with the corresponding tuning buttons 19 to 23. A conductor 28 common to all the voting (station-selecting) contacts, completes the return circuit for the several vote-discriminative tone generators 228 to 233, and is connected to each voting contact by the connection 33 and 29 to 32. The other and individual contacts of the tuning buttons 19 to 23 are connected to 34 to 38, the leads wherefrom are formed into the cable C. Of course, conductor 28 can also be placed within the then 6-conductor cable C although it has been shown separately in the attached figures.

Figure 3 is a view at right angles, taken on the line 3—3 of Figure 2, and shows the switching arrangements of a single tuning button. Like parts in the several figures having been given like numerals, they need not be again described. However, it will be seen that the additional elements are the spring contacts 40, 41 associated with key 19. Also shown are the spring grips 25 and their stops 25' which abut against the front of the tuning button of the broadcast receiver.

It will be understood that the common conductor 28 may be merely a metallic connection between the shafts of the individual push-buttons and the casing 18 if the latter were made of conducting material; alternatively, a separate metallic connecting circuit may be provided. Means may be required whereby the arrangements of Figure 2 can be adapted to a broadcast receiver wherein the push buttons are of various dimensions. This will require that the substitute buttons 19 to 23 shall be slidable in a groove longitudinally parallel to the line of push buttons of the broadcast receiver so that each substitute button is brought into alignment with the corresponding original receiver tuning button and then locked into place in proper position on the

groove. It may also be necessary to provide adjustments for the throw of the substitute buttons 19 to 23 of Figure 2, but this can generally be provided by having an excess throw available and then limiting the throw by that of the original buttons 12 to 16.

If knob or continuous tuning is used in the broadcast receiver, analogous or equivalent means are employed as shown in Figures 4 and 5 for controlling the tuning by a device which registers the preference or selection of the listener (respondent) automatically at the centercasting equipment and thus enables the automatic audit.

In Figure 4, 11 is the front panel of the receiver through which extends the rotary tuning shaft 42 which terminates in the tuning knob 43. An auxiliary shaft 46 extends through the wall of the casing 18, one end of said shaft being provided with the substitute tuning knob 51 and the other end having affixed thereto the strong spring grips 44, 45 which engage over the rim of knob 43, thereby causing 43 to be rotated whenever shaft 46 is rotated by the substitute tuning knob 51 of the auditing adjunct. On the shaft 46 is mounted a flat disc 48 in which a nearly circular slot 51 has been cut, shown more clearly in Fig. 5. It will be understood that any equivalent mechanical arrangement can be substituted. The disc in question is of insulating material. Projecting from the disc 48, which is locked to shaft 46 by suitable means 47, are a plurality of switch contacts 59 to 63, to which the respective flexible conductors 34 to 38 of the cable C are connected. These contacts 59 to 63 are adjustably set within the arcuate slot 51 and are adapted to coact with the remaining switch contact 50 to which conductor 28 is connected. The contact 50 is fixed in position and will make contact with the individual blades 59 to 63 at certain predetermined positions of the tuning knob 51 and shaft 46, these predetermined positions corresponding to the five stations most commonly selected for the purpose. It will also be understood that five stations have been chosen as illustrative only.

In Figure 5 the insulating disc 48 and its arcuate slot 51 are again shown, together with the five blades 59 to 63 which coact with the fixed contact 50 at the corresponding positions of the knob 51 and shaft 46. The flexible leads from the blade contactors are cabled into C, in which conductor 28 can also be included. The individual leads 34 to 38 extend to the centercasting respondent equipment where they are, as before described, connected to the right hand contacts of the transfer switch 7.

It is thus evident that either push-button or knob (continuous) tuning can be handled by the automatic-audit adjunct illustrated in the two embodiments described above. It will of course be understood that it is also possible to combine in the same auditing adjunct, push-button and knob tuning by merely connecting the corresponding group of contactors in parallel, and providing a six-pole double-throw switch generally similar to switch 7 of Fig. 1a, for changing from one group of parallel conductors to the other.

It will be clear from the above that I have provided a connection between a conventional broadcast receiver and the centercasting respondent equipment whereby turning on the broadcast receiver automatically turns on the centercasting equipment and switches the control of the voting buttons away from the centercasting equip-

ment and over to the tuning buttons of the automatic-audit adjunct at the broadcast receiver.

While I have shown and described certain preferred embodiments of the invention, it will be understood that modifications and changes may be made without departing from the spirit and scope of the invention as will be understood by those skilled in the art.

What I claim is:

1. In an adjunct device for externally fitting onto a radio signal receiver having exposed manipulatable tuning structure tunable to cause reception of any one of a plurality of radio signals transmitted in different frequency channels, and automatically indicating which radio signals are being received: signal selector mechanism including supporting structure having securing means for fitting the supporting structure externally over the exposed tuning structure to cover the tuning structure and provide an internal space bounded by externally available portions; said selector mechanism also including manipulatable control structure held on said supporting structure and operable, from said externally available portions, to any of a plurality of positions corresponding to the tuning to said plurality of radio signals; said selector mechanism also including actuatable linking elements held in the internal space of the supporting structure for connection to the tuning structure, and connected for movement by the control structure to transmit tuning manipulations from the control structure to the tuning structure; and indicator signal control elements also held in the internal space of the supporting structure for operation by the tuning manipulations to cause the generation of one of a plurality of different indicator signals indicative of the specific one of the different radio signals to which the receiver is tuned.
2. A combined voting and station audit system, comprising: a central radio station for selectively receiving and registering voting signals and signals corresponding to station selection preferences, a plurality of respondent radio stations each provided with a radio receiver having selector structure connected for tuning in programs from different broadcast stations, and provided with signal means for transmitting a plurality of voting and station selection signals to said central station; said signal means including a group of different signal-generating elements connected for selectable operation to individually generate signals selected from a predetermined group of different signals, voting structure connected for selectable actuation to individually energize the operation of said elements to generate a voting signal selected from said predetermined group of signals for indicating a reaction to a received program, selected from a group of voting reactions corresponding to said group of signals, and automatic switch structure connected to operate, upon suitable energization of the receiver, for automatically connecting said signal-generating elements to the station selector structure for indicating, by generating signals automatically selected by said selector structure from said group of signals, which one of a corresponding group of broadcast stations is being tuned in by the station selector structure.
3. In a system for effecting the automatic audit of the various radio broadcasting stations tuned in by a multiplicity of radio receivers each having manipulatable external tuning selector structure for selecting radio signals from one of

said stations, an adjunct device at each receiver covering the receiver's tuning selector and providing externally manipulatable control elements linked to the tuning selector structure as the only external means for operating said structure, indicating apparatus connected to said adjunct device for automatically producing different individual indications corresponding to the individual station being selected, said indicating apparatus including transmitting structure connected for automatically transmitting said produced indications, a central audit station including recording structure connected for collecting and recording said individual indications from the multiplicity of receivers in a systematic manner.

4. In an adjunct device for externally fitting onto a radio signal receiver having exposed manipulatable tuning structure to automatically indicate which of a plurality of different radio signals are being tuned in: cover structure having securing means for fitting the cover structure externally over the exposed tuning structure to cover the tuning structure; manipulatable control elements externally held on said cover structure and externally operable to any of a plurality of positions corresponding to the tuning to said plurality of radio signals; linking elements secured to said control elements and extending within said cover structure for connection to the covered tuning structure, and providing the sole means for manipulation of the covered tuning

5 structure from the exterior; and indicator signal control elements also held on said cover structure for operation by the tuning manipulations to cause the generation of one of a plurality of different indicator signals indicative of the specific one of the different radio signals to which the tuning structure of the receiver is tuned.

10 5. The combination as defined by claim 4 in which the manipulatable control elements include an interconnected set of selectable push-button controls for individual connection to a tuning selector of the selectable push-button type.

15 ALFRED N. GOLDSMITH.
